(57) **CLAIM**

The ornamental design for a display screen or portion thereof with graphical user interface to record listener effort score, as shown and described.

DESCRIPTION

FIG. 1 is a front view of a first image in a sequence for a display screen or portion thereof with a graphical user interface to record listener effort score, showing our new design;

FIG. 2 is a second image thereof;

FIG. 3 is a third image thereof; and,

FIG. 4 is a fourth image thereof.

The subject matter in this patent includes a process or period in which an image changes into another image. This process or period forms no part of the claimed design. The dashed lines showing the display screen and portions of the graphical user interface are directed to environment and form no part of the claimed design.
